UNITED STATES PATENT OFFICE.

PETER E. BURNS, OF SYRACUSE, NEW YORK, ASSIGNOR TO PASS & SEYMOORE, INC.,
OF SYRACUSE, NEW YORK, A CORPORATION OF NEW YORK.

CANOPY SWITCH.

Application filed March 9, 1927. Serial No. 174,021.

This invention relates to electric switches and more particularly to the operating member for such switches.

It is a general object of the present invention to provide a novel and improved form of electric switch.

More particularly it is an object of the invention to provide, in an electric switch, a novel operating means for the movable contact engaging member.

Specifically the invention resides in the provision of a rotatable switch stem in the form of a metal rod adapted to have a knob attached to one end thereof, the opposite end of the rod being flattened to provide two parallel faces, there being a strip of insulating material attached to each of the faces so that the two strips may straddle a movable contact engaging member to rotate the same.

Other and further objects of the invention will be more apparent to those skilled in the art upon a consideration of the accompanying drawing and following specification wherein is disclosed a single exemplary embodiment of the invention with the understanding that such changes may be made therein, as fall within the scope of the appended claims, without departing from the spirit of the invention.

In said drawing:

Figure 1 is a central vertical section of a switch constructed according to the present invention;

Figure 2 is a side elevation of the operating member; and

Figure 3 is a transverse section on line 3-3 of Figure 1.

In the usual construction of what are technically known as canopy switches, an insulating body is provided having a recess. Two contacts are arranged diametrically opposite on the walls of the recess and a more or less Z-shaped spring member is adapted to be rotated in the recess to have its ends engaged with these contacts to bridge the same. For the purpose of rotating the spring member it has been customary to provide a rod of insulating material such as fiber, having a slit in its end to receive the center portion of the Z-shaped spring. The outer end of this fiber rod was attached by suitable means to a threaded metal rod which rotated in a suitable bearing member and carried on its outer end an operat-

ing knob usually threaded to receive the end of the rod. Such an operating means is too expensive to manufacture owing to the fact that the fiber from which the insulating portion of the operator is formed into sheets and must then be sawed into square rods and finally turned into circular rods before it is ready to slit and attach to the threaded metal portion. Too many operations are involved and the expense of manufacture is therefore too great. The present invention contemplates a material improvement in the operating member which at the same time effects a great reduction in the number of operations and hence in the cost of producing the part.

Referring to the drawing, there is disclosed at 10 a suitably molded insulating body of any desired shape in plan, such as that shown in Figure 3, having the recess 11 therein receiving on its side walls which are suitably notched as at 11', two contacts but one of which, 12, is visible in Figure 1. These contacts are diametrically opposed and are adapted to be engaged to complete the circuit between the two by means of a substantially Z-shaped rotatable member 13 which is formed of spring metal such as bronze into the form shown in Figure 3 and having the central portion 14 and the wings or arms 15. In one position the wings engage the contacts 12 to bridge the same and in a position 90° therefrom the wings engage the walls of the recess 11 and the circuit between the contacts 12 is open. Suitable terminal members (not shown) lead from the contacts 12 to conductor wires extending from the insulating body. At 16 a portion of one of the extensions between the contact and the terminal wire is seen in section. A washer 17 is positioned on the top edges of the spring member and a suitable thin sheet of insulating material 18 covers the whole face of the insulating body 10 and closes the recess with the exception of the small circular opening 19 in the insulating member 18. A metal cover 20 is placed over the insulating member 18 and is secured in position by suitable fastening means. For purposes of illustration there are shown screws such as 21 passing thru the insulating body and received in threaded openings in the cover. This cover carries a metal bushing 22, the reduced end of which is spun over the edges of a hole in the pro-

jecting boss 23 of the cover 20. This bushing has a large bore 24 at its inner end and a smaller bore 25 at its outer end and is externally threaded to receive the nut 26 which secures the switch in position in the canopy wall 27.

In order to operate the switch, which is within the canopy, from outside of the canopy, an operating member is provided including the round metal rod 28 threaded throughout the majority of its length and having its one end flattened by a suitable stamping or swaging operation as shown best at 29 in Figure 1. Figure 2 shows how the width of the rod is increased by this flattening operation. The threaded portion of the rod is adapted for rotation in the bore 25 of the bushing. In order to connect the rod to the central portion 14 of the spring 13 it has applied to each face of the flattened portion one of the insulating strips 30. These strips are small rectangles of thin insulating material such as fiber, bakelite or the like. The thickness of the portion 29 is just slightly greater than that of the spring 14 so that when the two strips 30 are secured to the faces of the flattened portion 29 by the hollow rivet 31 or other suitable fastening means they are spaced apart a sufficient distance to readily straddle the central portion 14 of the spring. The length of the strips 30 is such that when the outer ends are substantially against the bottom of the recess in the insulating body the inner ends bear against the shoulder 32 at the junction of the two bores in the bushing and serve to prevent withdrawal of the operating member. A suitable knob 33 is internally threaded as shown in Figure 1 to be received on the threaded portion of the stem 28. The switch spring can be rotated in but one direction owing to the ratchet like formation in the walls of the recess in the insulating body and that direction is clockwise, and the thread is therefore right hand on the stem. Any attempt to reverse the direction of operation of the switch only serves to unscrew the nut and no damage can therefore be done to the movable spring member.

The construction of the switch operator is extremely simple as can be seen from Figure 2 where it comprises only the rod 28, usually a threaded brass rod which requires a single operation to flatten and punch to receive the rivet. A single punch press operation forms the strip 30 with the rivet hole therein and a single assembly operation joins the three parts together. The cost of manufacture is therefore extremely low.

Having thus described the invention, what is claimed as new and desired to be secured by Letters Patent is:

1. In an electric switch in combination,

stationary contacts, a movable conductor adapted to bridge said contacts, a rotatable operating stem for said switch formed of metal, a flattened end on said stem, a pair of insulating strips, one secured to each flat face, said strips straddling said movable conductor to operate the same.

2. In an electric switch in combination, an insulating body, stationary contacts thereon, a movable contact member adapted for rotation into and out of contact with said stationary contacts, an operating stem rotatable about its axis, a pair of insulating strips one engaging each side of said movable contact member, a flattened portion on said stem, said flattened portion fitting between said strips.

3. In a canopy switch in combination, an insulating body having a recess therein, opposed contacts on the sides of said recess, a substantially Z-shaped movable contact spring in said recess, a cover for said recess secured to said body, a metal rod rotatable in said cover and having an operating knob on the outer end thereof, a flattened inner end on said rod, a pair of insulating strips, one secured to each face of said flattened portion, said strips straddling the center of said Z-shaped spring for the purpose described.

4. An operating means for an electric switch, including in combination, a metal rod having a flattened end providing two substantially parallel oppositely disposed faces and an insulating strip secured to each face, said strips being spaced apart by the thickness of said flattened end of said rod.

5. An operating means for an electric switch, including in combination, a metal rod having a flattened end providing two substantially parallel outer faces, a pair of insulating strips each having one end overlapping said flattened rod end faces and a fastening means passing thru said strips and flattened end to secure them all together.

6. An operating means for a switch of the canopy type including in combination, a metal rod threaded at one end to receive a knob, the other end of said rod being flattened, a pair of substantially rectangular strips of insulating material fastened one on either face of said flattened portion, said strips extending beyond the end of said flattened portion for the purpose described.

7. An operator for the movable element of a canopy switch comprising a pair of insulating arms, portions of which are adapted to straddle said element and a metal rod between and secured to other portions of said arms.

In testimony whereof I hereunto affix my signature.

PETER E. BURNS.
